CLAIM

The ornamental design for a light enclosure, as shown and described.

DESCRIPTION

FIG. 1 is a front perspective view of a light enclosure showing our new design;

FIG. 2 is a right-side elevational view thereof;

FIG. 3 is a left-side elevational view thereof;

FIG. 4 is a front elevational view thereof;

FIG. 5 is a top plan view thereof;

FIG. 6 is a rear elevational view thereof;

FIG. 7 is a bottom plan view thereof;

FIG. 8 is a cross-sectional view taken along the lines 8-8 of FIG. 9; and,

FIG. 9 is a bottom perspective view thereof.

Throughout the drawings the broken lines depict portions of the light enclosure that form no part of the claimed design.
